Term of patent 14 years

(Cl. D56—1)

The circular area at the right-hand end of FIGURE 1 is a taut diaphragm lying in the plane of the upper surface of the instrument frame and has a rounded rim edge.

The dominant features of my new design are shown in solid lines in the drawing.

I claim:

The ornamental design for a stringed musical instrument, as shown and described.
